Primary Examiner — Carla Jobe Wright*(74) Attorney, Agent, or Firm* — Zhigang Ma(57) **CLAIM**

I claim the ornamental design for a protective cover for mobile phone, as shown and described.

DESCRIPTION

FIG. 1 is a perspective view of a protective cover for mobile phone;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent to the shaded surfaces represent the bounds of the claimed design. All other broken lines depict environmental subject matter. The unshaded interior of the case shown in FIGS. 1-2, the broken lines throughout the figures, and the unshaded areas bounded by broken lines form no part of the claimed design.
